UNITED STATES PATENT OFFICE

NORTON A. MEARS AND DIBRELL P. HYNES, OF CHICAGO, ILLINOIS, ASSIGNORS TO CHICAGO FORGING & MANUFACTURING CO., OF CHICAGO, ILLINOIS, A CORPORATION OF ILLINOIS

HOOD LATCH

Application filed September 11, 1931. Serial No. 562,263.

Our invention relates to an improvement in a lock mechanism and has for one purpose the provision of improved locking means for an automobile hood closure. One purpose is the provision of an externally operable lock for such a closure which will hold a hood latch in hood securing position and which will prevent the actuation of the normal external means for unlatching the hood. Other objects will appear from time to time in the course of the specification and claims.

The invention is illustrated more or less diagrammatically in the accompanying drawings, wherein:

15 Figure 1 is a side elevation of the exterior of an automobile hood;

Figure 2 is an interior elevation, on an enlarged scale;

20 Figure 3 is a section on the line 3-3 of Figure 2;

Figure 4 is a section on the line 4-4 of Figure 2;

Figure 5 is a section on the line 5-5 of Figure 2;

25 Figure 6 is a view similar to the right half of Figure 2, of a variant form; and

Figure 7 is a section on the line 7-7 of Figure 6.

Like parts are indicated by like symbols 30 throughout the specification and drawings.

Referring to the figures, A generally indicates a portion of a frame or chassis of an automobile. A¹ is the radiator and A² a forward part of the body. A³ A⁴ indicate abutments against which the double hinged hood closure A⁴ is adapted to be drawn.

Mounted upon the inner face of said closure is a rock shaft generally indicated as B having the terminal cranks B¹ and the intermediate off-set crank portion B². The rock shaft B may be supported at its ends in bearing members which include base plates C secured in any suitable manner to the inner face of the hood and the outstanding flange

45 C¹ which may be apertured as at C² to receive the rock shaft. Preferably the stock of the flange C¹ is upset as at C³, to provide what is in effect a cylindrical bearing of substantially greater length than the thickness of the

D indicates a base or assembly plate which may be secured in any suitable manner to the inner face of the closure A⁴. It may include ears D¹ D¹ curled over to form bearing sleeves for the intermediate portion of the rock shaft 55 B. They are shown herein as positioned closely adjacent the opposite ends of the off-set B². Referring for example to Figure 3 the base plate D is shown as provided with a cup portion inwardly off-set as at D² and provided with a bottom D³ apertured as at D⁴. Inset in the cup is a mating cup D⁵ with a reduced portion D⁶ which forms a cylindrical sleeve, the aperture of which is of the same diameter as D⁴. The two apertures thus form axially spaced bearings which receive the handle shaft D⁷ associated with the exterior handle D⁸.

Secured to the handle shaft D⁷ is a crank E which has associated with its outer end 70 the crank pin E¹. Pivoted to the pin E¹ is the securing stirrup E² which surrounds the off-set B² of the rock shaft B. It will be understood that rotation of the handle D⁸ in either direction rotates the rock shaft B through the engagement of the pin E¹ or the stirrup E² with the off-set B². The lever E is also provided with a shorter extension E³ at the opposite side of the shaft D⁷ which terminates in a toe E⁴ which closely abuts against the surface of the base plate D. The arc of rotation of the lever E is limited by the inwardly extending off-sets or abutments E⁵ E⁶ which are adapted to be engaged by said toe E⁴.

80 G G indicate locking abutments fixed upon the automobile structure. They include, for example, the base plates G¹ and the flanges G² with the inclined locking surfaces G³ adapted to be engaged by the cranks B¹ of the rock shaft B. The locking effect may, for example, be that which is more fully described in applicant's Patent No. 1,809,720, issued on the 9th day of June, 1931.

90 Referring to the form of Figures 1 to 3, H indicates any suitable lock housing which may be secured to the base plate D. The details of the lock form no part of the present invention but it may be actuated from the exterior of the hood closure as by any suit-

able key H^1 . It will be understood that rotation of said key moves the lock bolt H^2 in or out as the case may be. It will be seen, as in Figure 2, that when the bolt H^2 is in locking position, with the toe E^4 against the abutment E^5 , it holds the lever E in locking position or rather, prevents its escape from locking position. It is only after the bolt H^2 has been withdrawn that the handle D^8 can be moved into the dotted line position of Figure 2, thereby moving the cranks B^1 into the unlocking position as shown in dotted line in Figure 2.

Referring to Figures 6 and 7 the lock housing H is positioned above the rock shaft and the bolt H^2 engages the crank E , preventing its movement from the locking position in which it is shown.

It will be realized that whereas we have described and shown a practical and operative device nevertheless many changes may be made in size, shape, number and disposition and parts without departing from the spirit of our invention as defined by the scope of the claims. We, therefore, wish these drawings to be taken as in a broad sense illustrative and diagrammatic rather than limiting us to the precise details of our description and showing.

The use and operation of the invention are as follows:

We have illustrated a hood latch in general accordance with the showing of our Patent No. 1,809,720, issued the 9th day of June, 1931. It will be understood, for example, that the flexure of the rock shaft B , when the parts are in locking position, serves to hold the lever E in the locking position with the toe E^4 against the abutment E^5 , the position in which it is shown in Figures 2 and 6. It will be observed that the lever E is slightly over center and therefore the locking flexure of the rod prevents it from returning over center unless a positive twist or movement is manually given to the handle D^8 . In order to prevent the opening of the hood by unauthorized parties we may position the lock housing H so that the keeper H^2 will engage either the toe E^4 or the crank pin E , to prevent movement of the handle D^8 to unlocking position.

We claim:

1. In a latching device for a double hinged hood including a rock shaft rotatably mounted on the inner face of the hood, and means for rotating said rock shaft, including a handle exterior to the hood, bearing means for the rock shaft, including brackets secured to the inner face of the hood closure and having each a flange apertured to permit the passage of the rock shaft therethrough, said aperture having associated therewith a generally cylindrical bearing member extruded from said flange.

2. In a latching device for a double hinged

hood including a rock shaft rotatably mounted on the inner face of the hood, and means for rotating said rock shaft, including a handle exterior to the hood, bearing means for the rock shaft, including brackets secured to the inner face of the hood closure and having each a flange apertured to permit the passage of the rock shaft therethrough, said aperture having associated therewith a generally cylindrical bearing member extruded from said flange, said bearing member being apertured in extension of the aperture of the flange, and continuing the inner surface thereof at a substantially uniform diameter.

Signed at Chicago, county of Cook, and State of Illinois, this 9th day of September, 1931.

NORTON A. MEARS.
DIBRELL P. HYNES.
